UNITED STATES PATENT OFFICE.

JOHN WADE, OF ST. PAUL, MINNESOTA.

DESIGN FOR A VEHICLE-BODY.

53,388.

Specification for Design.

Patented May 27, 1919.

Application filed March 8, 1917. Serial No. 153,517. Term of patent 14 years.

To all whom it may concern:

Be it known that I, JOHN WADE, a subject of the King of Great Britain, residing in the city of St. Paul, county of Ramsey, and State of Minnesota, have invented a new, original, and ornamental Design for Vehicle-Bodies, of which the following is a specification, reference being had to the accompanying drawing, forming part thereof.

Figure 1 is a front perspective view of a

vehicle body, showing my new design and Fig. 2 is a rear perspective view thereof.

I claim:

The ornamental design for a vehicle body, as shown.

JOHN WADE.
